IMPELLER PUMP

Emile Egger, Cressier-pres-Neuchatel, Switzerland

Filed Sept. 16, 1957, Ser. No. 684,328

4 Claims. (Cl. 259—9)

The present invention relates to impeller pumps and more particularly to an impeller pump for simultaneously transporting and homogenizing an inhomogeneous liquid.

The impeller pumps according to the prior art are capable of transporting liquid, but cannot produce a mixing of the liquid by which an inhomogeneous liquid is homogenized while passing through the pump.

It is one object of the present invention to overcome this disadvantage of the known impeller pump constructions, and to provide an impeller pump capable of simultaneously mixing and transporting an inhomogeneous liquid.

It is another object of the present invention to provide an impeller whose vanes are shaped in a particular manner to produce a thorough mixing and homogenizing of a liquid transported thereby.

It is another object of the present invention to provide impeller vanes which are shaped contrary to the hydraulic principles applied in conventional pumps, and for the purpose of tearing the liquid stream entering the pump so that the liquid separates from the trailing faces of the impeller vanes to create zones of reduced pressure behind the trailing faces of the impeller vanes.

It is also an object of the present invention to provide for the impeller, a tubular stator which is curved so that the pumped liquid enters the stator in horizontal direction, and leaves the stator in vertical direction.

A further object of the present invention is to provide an impeller pump capable of transporting and mixing a liquid entering through a pump inlet which communicates with the atmosphere.

With these objects in view, the present invention mainly consists in a pump for homogenizing and transporting an inhomogeneous liquid, the pump comprising, in combination, a tubular stator member, and an impeller located in the tubular stator member adjacent the inlet thereof, the impeller including a hub portion and a plurality of impeller vanes which are shaped for not only transporting a liquid, but also for forcing the liquid to separate from at least a surface portion of the trailing faces of the impeller vanes, while the liquid passes along the leading faces of the vanes. Thereby, zones of reduced pressure are created behind the trailing faces of the impeller vanes which results in a thorough mixing of the liquid until the same is rendered homogeneous.

The front edges of the impeller vanes, that is the edges facing the inlet of the pump, have a radius of curvature, a thickness, and general shape which effects a tearing of the liquid stream entering the pump, so that the liquid separates from the trailing faces of the impeller vanes at least in the region of the front edges. The turbulence created thereby effects the homogenizing of the liquid, which however passes in a laminar flow along the leading faces of the impeller vanes. The zones of reduced pressure behind the trailing faces of the impeller vanes, also permit the pumping of liquid having a high content of gases which pass from the liquid into the zones of reduced pressure. The vacuum in the zones of reduced pressure

also serves to accelerate the liquid, and permits it to connect the pump inlet to the atmosphere so that the pumped liquid can be supplied to the pump in an open stream.

According to the preferred embodiment of the present invention, the tubular stator of the pump is curved and has a horizontal inlet portion and a vertical outlet portion. The impeller according to the present invention is arranged in the inlet portion of the curved tubular stator, and has a horizontal axis. Thereby, the liquid pumped by the impeller is raised to a higher level.

The novel features which are considered as characteristic for the invention are set forth in particular in the appended claims. The invention itself, however, both as to its construction and its method of operation, together with additional objects and advantages thereof, will be best understood from the following description of specific embodiments when read in connection with the accompanying drawings, in which:

Fig. 1 is an axial sectional view of an impeller pump according to the present invention; and

Fig. 2 is a transverse section of an impeller vane according to the present invention taken on line 2—2 in Fig. 1.

Referring now to the drawings, and more particularly to Fig. 1, a tubular stator 1 has a circular inlet 2 and a circular outlet 3 having the same diameter as inlet 2. The inlet 2 is located in a vertical plane, and the outlet 3 is located in a horizontal plane, and the tubular stator is constituted by an elbow pipe. An opening 4 is provided in the tubular stator member 1, a drive shaft 5 passing through the opening 4. Bearing means 6 are secured to the stator 1 and include bearings 7 supporting shaft 5 for rotation about a horizontal axis which coincides with the axis of the circular inlet 2, and with the axis of the annular surface 1a adjacent the inlet 2.

The impeller 10 is secured to the end of shaft 5, and includes an impeller hub 11 which is hollow and streamlined.

A plurality of impeller vanes 12 is secured to the hub 11, each impeller vane having a root portion 13 projecting into a hole 14 in the impeller hub and being secured to the hub 11 by suitable means 15 located inside the hollow impeller hub 11.

It is evident that rotation of the drive shaft 5 will effect transportation of a liquid entering the inlet 2 through the tubular stator 1 until the liquid leaves through the outlet 3.

In accordance with the present invention it is not only desirable to transport the liquid to a higher level, but also to render the pump capable of pumping inhomogeneous liquids while simultaneously mixing such liquids until the same are completely homogeneous.

Known impeller pumps are designed in accordance with hydraulic principles so that all the liquid entering the pump inlet moves along the leading faces and trailing faces of the impeller vanes. The impeller vanes according to the present invention are designed and constructed contrary to the accepted hydraulic principles, since in accordance with the present invention it is not desired that the liquid flow in a continuous flow along leading and trailing faces of the impeller rings.

The particular shape of the vanes by which a separation of the pumped liquid is obtained at least part of the trailing faces of the impeller vanes, depends on many factors, for example the viscosity of the liquid, the ratio between the solid content and the liquid part of the respective liquid, the speed of rotation of the impeller, and it is difficult to give a theory of the construction of the impeller vanes according to the present invention. However, it will be understood that the impeller vanes according to the present invention have to be shaped in order to produce separation of the respec-

tive liquid from the trailing faces of the impeller vanes when the impeller rotates at a selected speed.

It has been found after considerable experimentation by testing practical embodiments of the present invention, that if such separation of the pumped liquid occurs at the trailing faces of the impeller vanes, a liquid which enters the pump in inhomogeneous condition will be rendered homogeneous within the pump due to the action of the impeller vanes according to the present invention.

Fig. 2 shows a cross section of an impeller vane according to the present invention. The impeller vane 12 is secured to the hub 10 with the convex surface 12b facing toward inlet 10, and has a shape which is different from the shape of the cross section of conventional impeller vanes. Hub 10 is rotated by shaft 5 in such a direction of rotation that the convex face 12b leads and the concave face 12a trails. The thickness 20 in the region of the front edge of the impeller vanes is about three times the thickness 21 in the region of the rear edge of the impeller vanes. The front edge portion 22 is strongly curved toward the trailing face 12a of the impeller vane 12, whereas the rear edge portion 23 has a lesser curvature. The radius of curvature of the front edge 22' is greater than the corresponding radius in conventional impellers, and the angle of the front edge portion 22 with respect to a plane perpendicular to the axis of rotation of the impeller, has to be carefully chosen to obtain the desired result.

When the impeller vane according to the present invention is properly designed for the particular viscosity and consistency of the liquid to be pumped and mixed, the liquid entering the pump parallel to the axis of rotation 30 of the impeller, will be torn behind the front edges 22' of the impeller vanes 12, and will separate from the trailing face 12a at least adjacent the front edge 22' but preferably along the entire trailing face 12a, as illustrated by the shaded area 25. At the same time, the liquid flows along the convex leading faces 12b of the impeller vanes, as indicated by the arrows 26. In the region of the concave trailing faces 12a, the liquid will flow in direction of the arrows 27 so that directly adjacent the trailing faces 12a, a vacuum zone of reduced pressure is created. The liquid passing in direction of the arrows 27 creates a zone of turbulence behind the rear edges of the vanes resulting in thorough mixing and homogenizing of the liquid.

Impeller vanes of this type have a twisted shape, and in order to obtain the best possible results, the outermost portions of the vanes, which move at the highest speed, are shaped in accordance with the present invention.

A part of the driving power is used for mixing the liquid, whereas in conventional impeller pumps, all the driving power is used for transporting the liquid. On the other hand, due to the formation of a zone of reduced pressure behind the trailing faces of the impeller vanes, the speed of entry of the liquid is increased since the vacuum zones produce a suction effect.

If the cross section of a conventional impeller vane is compared with the impeller vane according to the present invention, it will be found that the conventional vane is thinner, less curved, and has a front edge portion defining a smaller angle with a plane perpendicular to the axis of rotation. The shape of a vane according to the present invention corresponds to a certain extent to the shape of a wing of a slow flying airplane, whereas the conventional vane has a shape corresponding to the shape of a wing of a fast flying plane in which no separation of the air is desired. In a slow flying plane, the creation of a vacuum zone underneath the wing is desired for producing a greater lift.

It will be understood that each of the elements described above, or two or more together, may also find a useful application in other types of impeller pumps differing from the types described above.

While the invention has been illustrated and described as embodied in an impeller pump having impeller vanes creating a zone of reduced pressure behind the trailing faces thereof, and having as stator an elbow pipe, it is not intended to be limited to the details shown, since various modifications and structural changes may be made without departing in any way from the spirit of the present invention.

Without further analysis, the foregoing will so fully reveal the gist of the present invention that others can by applying current knowledge readily adapt it for various applications without omitting features that, from the standpoint of prior art, fairly constitute essential characteristics of the generic or specific aspects of this invention and, therefore, such adaptations should and are intended to be comprehended within the meaning and range of equivalence of the following claims.

What is claimed as new and desired to be secured by Letters Patent is:

1. A pump for homogenizing and transporting an inhomogeneous liquid and comprising, in combination, a curved tubular stator member having an inlet portion terminating in a circular inlet and an outlet portion transverse to said inlet portion and terminating in a circular outlet; an impeller having an axis of rotation coaxial with said circular inlet, said impeller being located in said tubular stator member adjacent said inlet and including a hub portion and a plurality of impeller vanes projecting from said hub portion, said impeller vanes being shaped for transporting to said outlet an inhomogeneous liquid entering said inlet, each of said impeller vanes having a front edge portion facing said inlet and a rear edge portion, and having in a transverse section a convex leading face and a concave trailing face connecting said front edge portion and rear edge portion, said convex faces of said vanes facing toward said inlet, a first portion of said trailing face located adjacent said front edge portion being more concave than a second portion of said trailing face adjacent said rear edge portion, said front edge portions having a selected radius of curvature and a selected thickness whereby during rotation of said impeller at a selected speed the liquid is forced to separate at least from said first portion while passing along the leading faces of said impeller vanes whereby zones of reduced pressure are created behind said first portions of said trailing faces and the liquid is rendered homogeneous; and means for rotating said impeller at said selected speed with said convex faces leading and said concave faces trailing.

2. A pump for homogenizing and transporting an inhomogeneous liquid and comprising, in combination, a tubular stator member having an inlet and an outlet; an impeller located in said tubular stator member and being rotatable in one direction about an axis of rotation, said impeller including a hub portion, and a plurality of impeller vanes projecting from said hub portion, said impeller vanes being shaped for transporting to said outlet an inhomogeneous liquid entering said inlet, each of said impeller vanes having a front edge portion confronting said inlet and a rear edge portion, and having in a transverse section a convex leading face and a concave trailing face connecting said front edge portion and rear edge portion, said convex faces of said vanes facing toward said inlet; and means connected to said hub portion for rotating said impeller in said one direction of rotation with said convex faces of said vanes leading and said concave faces trailing whereby during rotation of said impeller the liquid is forced to separate from said concave trailing faces while passing along said convex leading faces of said vanes whereby zones of reduced pressure are created behind said trailing faces, and turbulence is created behind said trailing edges and the liquid is rendered homogeneous.

3. A pump for homogenizing and transporting an inhomogeneous liquid and comprising, in combination, a tubular stator member having an inlet and an outlet, and

a cylindrical surface adjacent said inlet; an impeller rotatable in one direction about an axis of rotation coinciding with the axis of said cylindrical surface and located in said tubular stator member, said impeller including a hub portion and a plurality of impeller vanes projecting from said hub portion toward said cylindrical surface, said impeller vanes being shaped for transporting to said outlet an inhomogeneous liquid entering said inlet, each of said impeller vanes having a front edge portion confronting said inlet and a rear edge portion, and having in a transverse section a convex leading face and a concave trailing face connecting said front edge portion and said rear edge portion, said convex faces of said vanes facing toward said inlet, a first portion of said trailing face located in the region of said front edge portion being more concave than a second portion of said trailing face located in the region of said rear edge portion; and means connected to said hub portion for rotating said impeller at a selected speed in said one direction with said convex faces leading and said concave faces of said vanes trailing so that the liquid is forced to separate from said trailing faces while passing along the leading faces of said impeller vanes whereby zones of reduced pressure are created at least behind said first portions of said trailing faces and turbulence is created behind said rear edge portions whereby the liquid is rendered homogeneous.

4. A pump for homogenizing and transporting an inhomogeneous liquid, and comprising, in combination a tubular stator having an inlet and an outlet and an annular surface between said inlet and outlet; and an impeller 30 rotatable in one direction and having an axis of rotation coaxial with said annular surface and located in said tubular stator member adjacent said inlet, said impeller in-

cluding a hub portion, and a plurality of impeller vanes projecting from said hub portion toward said annular surface, said impeller vanes being shaped for transporting to said outlet an inhomogeneous liquid entering through said inlet, each of said impeller vanes having a front edge portion confronting said inlet and a rear edge portion, and having in a transverse section a convex leading face and a concave trailing face connecting said front edge portion and said rear edge portion, said convex faces of said vanes facing toward said inlet, said front edge portions having a selected radius of curvature and a selected thickness, the thickness of each impeller vane in the region of said front edge portion being substantially three times the thickness of said rear edge portion; and means connected to said hub portion for rotating said impeller in said one direction at a selected speed with said convex faces leading and said concave faces of said vanes trailing so that the liquid is forced to separate at least from said trailing faces while passing along the leading faces of said impeller vanes whereby zones of reduced pressure are created behind said trailing faces and turbulence is created behind said trailing edges whereby the liquid is rendered homogeneous.
